UNITED STATES PATENT OFFICE.

JOHN T. BRADSHAW, OF TRENTON, NEW JERSEY.

WATER-CLOSET BOWL.

1,184,718.

Specification of Letters Patent.

Patented May 30, 1916.

Application filed August 12, 1915. Serial No. 45,142.

To all whom it may concern:

Be it known that I, JOHN T. BRADSHAW, a citizen of the United States, residing at Trenton, in the county of Mercer and State of New Jersey, have invented certain new and useful Improvements in Water-Closet Bowls, of which the following is a specification, reference being had to the accompanying drawings.

10 This invention relates to water closet bowls, and particularly to that type of bowl having a flushing rim.

15 The general object of my invention is to so form the bowl that the rim shall be sanitary at those parts of the rim which are particularly liable to become soiled, and in this connection provide means for effectively flushing those parts of the rim.

20 A further object is to so form the bowl and the flushing rim that the bowl will be flushed for its full diameter and for its full height. And another object is to flush both the back and front of the bowl by fan-like sheets of water projected horizontally from 25 opposite terminal portions of the rim.

A further object is to so form the bowl that the front wall shall be relatively thin so that only a very small surface likely to soil is presented.

30 Still another object is to attain the advantages above referred to without increasing the cost or difficulty of making the bowl but on the contrary reducing the cost.

35 My invention is illustrated in the accompanying drawings, wherein:

Figure 1 is a vertical section of a closet bowl constructed in accordance with my invention; Fig. 2 is a top plan view; Fig. 3 is a transverse section of the construction 40 shown in Figs. 1 and 2; Fig. 4 is a vertical fragmentary section of the rear end of a bowl; Fig. 5 is a vertical section of the forward end of a modified form of bowl; Fig. 6 is an enlarged fragmentary section at the 45 forward end of the bowl, the section being taken through the flushing rim.

In the ordinary closet bowls the parts of the bowl most liable to be soiled are the front of the bowl and the rear thereof. To obviate 50 this, bowls have been devised in which the forward portion of the bowl is forwardly extended to receive the urine, and the rear end of the bowl is rearwardly offset or extended to form a continuation of the seat opening. No means however have been provided for efficiently flushing the vertical

inner surfaces of the front and rear walls of these offsets, except to some extent beneath the rim of the bowl. These objectionable features are avoided by the construction 60 now to be described.

The bowl 2 is of any usual or suitable design, and except in the details hereafter pointed out may be of any construction. Of course the bowl is to be made of earthenware, porcelain, or like material. The bowl 65 is shown as formed with the usual legs 3 and 4 of the siphonic discharge and with the usual distributing chamber 5.

As shown in Fig. 2, the bowl is substantially elliptical in plan and has the generally elliptical opening 6. The sides of the bowl are thickened so as to form overhanging rim portions 7, these rim portions being relatively deep. At the front of the bowl, 70 however, these thickened portions terminate, as at 8, and merge into a relatively thin and shallow rim 9 which very slightly overhangs the body of the bowl. The faces 75 8 of the rim portions 7 are disposed at a slight inclination to the vertical. Inasmuch as the rim portions 7 terminate at 8, an extension 10 of the seat opening 6 is formed. At the rear, the rim portions 7 terminate at 11 and extend upward and 80 rearwardly and merge into the relatively shallow or thin slightly overhanging rim 12.

A waterway 13 extends around the rear 85 end of the bowl and is in communication with the chamber 5. This waterway or 90 passage extends through the length of each rim portion 7, as shown by dotted lines Fig. 2. The lower face of each rim portion is formed with elongated perforations 14 for the discharge of water into the bowl. The 95 end face 8 of each rim portion 6 is also perforated so that jets of water are discharged horizontally across the surface of the front end of the bowl below the rim 9 and also downwardly at a slight angle to the horizontal.

The rear end face of each rim portion is also perforated so that jets of water are discharged across the face of the rear end of the wall 15 below rim 12. Inasmuch 100 as the terminal faces merge gradually into the under faces of the rim sections, the jets from the ends of the rim sections will be projected at different angles so that a fan-shaped sheet of water will be ejected across the front and rear end faces of the bowl.

110 In Figs. 4 and 5 I show a slightly modified form of my invention as applied to

those closets whose bowls are formed with lips at their forward or rear ends, or both. In these closets the side rim sections 7^a merge at the forward ends into the rim 9^a which extends above the level of the upper edge of the bowl. This rim 9^a overhangs slightly, and the forward ends of the rim portions 7^a are each provided with a slot 14^a discharging a fan-shaped jet, not only across 10 the inner face of the lip but upward against the overhanging flange or rim 9^a. The rear lip 12^a is also raised above the general level of the top edge of the bowl, and the jet opening 14^a discharges upward against the 15 rim 12^a. It is to be noted that in my construction the forward portion of the bowl is not extended, but the extension 10 of the bowl opening is formed by reducing the thickness and depth of the rim. By thinning the rim at the front, I reduce the surface subject to contamination when the 20 closet is used as a urinal.

The ordinary closet is flushed over the top of the bowl all the way around, necessitating a water way either within or on top of the bowl and this reduces the size of the bowl opening. A bowl constructed in accordance with my invention can be flushed in every part for the entire circumference 30 of the bowl and to the full height of the bowl between the flushing rims.

The bowl is simple in design and can be cheaply made.

Having thus described my invention, 35 what I claim is:

1. A closet bowl having on each side an overhanging flushing rim portion, the forward ends of the rim portions terminating at each side of the bowl opening, the forward ends of the rim portions forming the sides of a forward extension of the bowl opening and being perforated to cause the discharge of water transversely across the front part of the bowl between the ends of 40 the rim portions, said forward wall having a relatively thin and slightly overhanging rim.

2. A closet bowl having on each side an overhanging flushing rim portion, the for-

ward and rear ends of the rim portions terminating at each side of the bowl opening and said ends defining and forming the sides respectively of the forward and rear extension of the bowl opening and being perforated to cause the discharge of water transversely across the front and rear walls of the bowl between the ends of the rim portions, said forward and rear walls between the ends of the rim portions having a relatively thin and slightly overhanging rim.

3. A closet bowl having on each side an overhanging flushing rim portion, the like ends of the rim portions terminating at each side of the bowl opening and defining an extension of the bowl opening, the bowl wall between the adjacent ends of the rim portions being formed to provide a relatively thin slightly overhanging rim, the ends of the first-named rim portions being formed with perforations discharging upward against the overhanging thin rim across the wall and downward across the wall.

4. A closet bowl having on each side an overhanging rim portion, the forward and rear ends of the rim portions terminating at each side of the bowl opening and defining the sides of a forward extension of the bowl opening, the forward and rear walls of the bowl between the terminal ends of the flushing rim portions being upwardly and forwardly extended to form lips, each of said lips having a relatively thin slightly overhanging rim, the ends of said first-named rim portions being perforated to cause the discharge of water transversely across the front and rear walls of the bowl, between the ends of the rim portions and upward against the overhanging rim of 90 said lips.

In testimony whereof I hereunto affix my signature in the presence of two witnesses.

JOHN T. BRADSHAW.
